UNITED STATES PATENT OFFICE.

MARIUS OTTO, OF PARIS, FRANCE.

ARRANGEMENT FOR THE SUPPORT AND COOLING OF STATICL OZONIZERS.

SPECIFICATION forming part of Letters Patent No. 733,674, dated July 14, 1903.

Application filed May 28, 1903. Serial No. 158,899. (No model.)

To all whom it may concern:

Be it known that I, MARIUS OTTO, doctor of science, of No. 5 Avenue du Bois de Bologne, Paris, France, have invented a certain new and useful Improved Arrangement for the Support and Cooling of Statical Ozonizers; and I do hereby declare the following to be a full, clear, and exact description of the invention, such as will enable others skilled in the art to which it appertains to make and use the same.

Ozonizers formed of plates of glass have many serious disadvantages, one of the most important of which is the overheating of the dielectric and the rupture which results. To avoid this cause of trouble, a suggestion has been made of circulating a stream of water around the glass plates or plunging them into a mass of water. It has also been suggested that the armatures which protect the dielectric substances should consist of hollow casings within which a cooling liquid is caused to circulate; but all these methods present great difficulties in the way of insulation and convenience of installation.

The arrangement for supporting and cooling statical ozonizers which is the subject of the present application for a patent enables the problem to be solved in a manner both simple and practical.

The invention is represented in detail in the accompanying drawings, in which—

Figure 1 is a diagrammatic representation of the apparatus. Figs. 2, 3, and 4 represent, respectively, a side elevation, a front elevation, and a plan of a practical form for the construction of the apparatus.

A sheet of iron *a*, provided at its upper end with an air-chamber *b* and an exhaust-pipe *c*, is suspended between two plates of glass *d*, which are held at a suitable distance by insulating-clamps made of glass. To the exterior surface of each of these two plates of glass is fixed a metallic conducting-surface *e*, covered with a layer of felt *f*. The whole arrangement is firmly secured by screws to the metallic supports *g*. Two perforated metal tubes *h* and *i* allow of the felt layers *f* being continuously sprinkled with water.

The two exterior electrodes are connected to earth at *t*. Only the metallic sheet *a* is insulated and is connected by means of the wire *l* with one of the poles of a transformer *m* at high tension, of which the other pole is led to earth.

When the apparatus is in working order, the electric sparks leap the interval between the sheet *a* and the interior surface of the dielectric *d*. Air flowing in the direction indicated by the arrows intersects these sparks.

In the form of construction represented by Figs. 2, 3, and 4 five static ozonizers are grouped on the same metallic base.

Each of the portions of the apparatus is constituted as has been described above, and consists of a metallic sheet *a*, suspended between two dielectric substances *d*. Only one of these portions is shown in detail. The other four are indicated by the armatures *g*, which inclose them. The two dielectric substances *d* carry on their exterior surface a conducting-electrode *e* and a layer of felt *f*, which is sprinkled continuously by a stream of water. The external electrodes *e* are joined to earth, and thus avoid any difficulty of insulating the stream of water.

A discharge-indicator *n*, having a movable shutter, completes the apparatus. The central electrode is insulated by a glass tube *k*.

It is advisable to complete the mounting of the apparatus with a sparking device *p*, Fig. 1, to act as an automatic protector consisting of two bent metallic rods. By means of a screw these two rods can be approached together to such a degree that the operating of the sparking device will be certain as soon as the potential has reached a limit dangerous to the security of the apparatus.

I claim—

An apparatus for supporting and cooling statical ozonizers characterized by a metallic electrode *a* suitably insulated by means of a box *b*, and an exhaust-pipe *c* for withdrawing the ozonized air, the said metallic electrode being supported between two dielectric surfaces *d* which are covered on the exterior by a conductor *e* and cooled continuously by a spray of water which saturates a layer of porous

material *f* such as felt or any other suitable substances, and a sparking device of which one of the ends is joined to earth and the other connected with the central electrode *a*, forming a kind of electrical safety-valve for the whole apparatus.

In testimony whereof I have hereunto set

my hand in the presence of two subscribing witnesses.

MARIUS OTTO.

Witnesses:

ANDRÉ MOSTICKE,
AUGUSTUS E. INGRAM.
